UNITED STATES PATENT OFFICE.

CHARLES W. CLODFELTER, OF FALL RIVER, MASSACHUSETTS.

SHIFTING STAGE.

1,384,180.

Specification of Letters Patent. Patented July 12, 1921.

Application filed June 29, 1920. Serial No. 392,800.

To all whom it may concern:

Be it known that I, CHARLES W. CLODFELTER, a citizen of the United States, and a resident of Fall River, in the county of 5 Bristol and State of Massachusetts, have invented certain new and useful Improvements in Shifting Stages, of which the following is a specification.

My invention relates to staging or scaffolding devices such as are employed by 10 painters and the like and more particularly to supporting means adapted to hold and shift such a stage or scaffold, and has for one of its objects to permit the same to be easily 15 moved quickly and safely and to be securely placed at any desired position.

The invention consists in the novel construction, arrangement and combination of various elements and parts, set forth in the 20 claims hereof, one embodiment of which is shown in the accompanying drawings and is hereinafter more particularly described.

In the said drawings Figure 1 is a side elevation of a device constructed according 25 to my invention, looking outward from the wall of the building in connection with which it is used; Fig. 2 is an end view of the same; Fig. 3 is an elevation of one of the supplementary supporting devices looking 30 in the other direction from that shown in Fig. 2; Fig. 4 is a view of the said supporting device taken at right angles to Fig. 3, the said Figs. 3 and 4 showing more particularly the form of such supporting device which is used as an extension to the 35 main supporting device when necessary, as hereinafter more particularly described; Fig. 5 is a detail view showing the upper part of one of said supporting devices, and 40 Fig. 6 is a detail view of one of the sliding sleeves forming part of the invention, as hereinafter explained.

In carrying my invention into effect in the embodiment thereof which I have selected 45 for illustration in the accompanying drawings and description in this specification, I provide a pair of supporting members 11, each of which is provided at its upper end with sockets 13 adapted to receive a hook 14, 50 which may be inserted in either one of said sockets, as shown more particularly in Fig. 5, where said hook is shown in full lines inserted in the left-hand socket and in dotted lines as if placed in the right-hand 55 socket. The hooks 14 are adapted to be placed over the cornice or edge of a roof

of a building or other structure and thereby maintain the supporting members 11 in position.

Mounted upon said supporting members 60 11 are sliding frames (see Fig. 2) each of which comprises guiding sleeves 15 fitting over said supporting members 11, and a vertical connecting member 16. Each sleeve of the lower pair is provided with a second 65 sleeve 17 secured laterally thereto (see Fig. 6).

In each of said sleeves 17 is located a supporting beam 18 (see Fig. 2) which bears at each end a wheel or roller 19, shown 70 as of different sizes, though this is not essential, adapted to bear against the wall of the building or structure in connection with which the stage is to be used, this wall being designated 20 in the drawings. The 75 beams 18 are provided with notches 21 adapted to engage with rings 22 which are connected by a chain 23 to the upper sleeve 15, thus serving to support the ends of the beams 18. The ends of the stage proper, 80 designated 24, rest upon the beams 18 and are secured thereto by hooks 25, secured to the stage by nuts 26, and the lower ends of which are adapted to engage with the notches 21 in the beams 18; by this means 85 the stage may be adjustably secured at any point on the beams 18. The sliding frames and the beams and stage supported thereby, are raised and lowered by means of ropes 27 passing through pulleys 28 in a manner 90 which will be well understood.

The supporting members 11 are provided with sockets 29, and the sliding frames located on said supporting members are provided with pawls 30 adapted to engage 95 with the said sockets. The said supporting members are also provided with guides 31 (see Fig. 1) which are adapted to deflect the pawls 30 when the sliding frames are lowered, so that said pawls will not engage 100 with said sockets, but to guide said pawls toward said sockets when the supporting frames are raised.

In connection with the parts of the apparatus which have been described, I may 105 also provide a sliding seat 32 (see Fig. 2), the use of which will be hereinafter explained; this seat is provided with a pawl 33 analogous to the pawls 30, and likewise adapted to engage with the sockets 29.

In Fig. 2 the invention is shown in use as it would be when supported from a cornice

which projects some distance out beyond the wall of the building. When it is desired to use the apparatus upon a building which has no projecting cornice, or one which projects but a slight distance, the hooks 14 are removed from the sockets in which they are shown in Fig. 2 and in full lines in Fig. 5, and are placed in the opposite sockets, as shown by the dotted lines in Fig. 5, and the apparatus reversed, so that the supporting members 11 then lie nearer to the wall of the building, and the platform 24 is outside of the supporting members, instead of being between the supporting members and the wall as shown in Fig. 2.

When the apparatus is used in connection with a structure higher than the length of the supporting members 11, I secure to the lower end of the said supporting members 11, additional or supplementary supporting members 12, such as are shown in Figs. 3 and 4, and which are provided with hooks 34 at their upper ends which engage with sockets in the lower ends of the main supporting members 11.

These additional supporting members 12 are provided with pawl engaging sockets 29 and guides 31, analogous to those already described.

The operation of my invention is as follows: When the apparatus is to be used upon a building having a cornice or the like projecting forward from the front of the building a substantial distance, the apparatus is used in the form shown in Fig. 2, the suspending hook 14 being inserted in the socket in the supporting member 11 as shown in said Fig. 2 and in the full lines in Fig. 5. The sliding frames comprising the sleeves 15, the horizontal supporting members 18, the platform 24, and the chain 23 are then all in the relative positions shown in said Fig. 2. The platform can then be raised or lowered by the rope 27 in the usual manner which will be well understood, the large wheel 19 on the left in Fig. 2 bearing against the wall 20. The pawls 30 are adapted to engage with the sockets 29 and support the platform at any desired elevation. The platform may then be raised step by step, the pawls 30 engaging with successive sockets 29, but when it is desired to lower the same, the pawls 30 are deflected by the guides 31 so that they do not engage with the sockets 29 and the platform may so be lowered to the full extent. If the height of the building requires, the additional supporting members 12 may be secured to the lower ends of the principal supporting members 11 by the hooks 34 in an obvious manner.

If it is desired to raise or lower the platform, without the necessity of the operator

remaining thereon during such raising or lowering operation, the operator may sit or stand upon the seat 32, which may be located at any desired position upon one of the supporting members, the pawl 33 maintaining the same in position by engaging with one of the sockets 29.

When the apparatus is to be used upon a building which is not provided with a forwardly extending cornice, the hooks 14 are inserted in the sockets on the other sides of the supporting members 11, as shown in the dotted lines in Fig. 5, and the said supporting members then hang in closer relation to the wall of the building, and in that case the small wheels or rollers 19 in the ends of the horizontal supporting members 18 bear against the wall of the building.

The advantages of my invention will be obvious from what has been above said with regard to its construction and method of operation.

I do not limit myself to the particular form, construction or combination which I have described in the specification and shown in the accompanying drawings, as it is obvious that various modifications of the same could be made without departing from the spirit and scope of the invention.

Having thus described my invention, what I claim as new and desire to secure by Letters Patent is as follows:

1. In a shifting stage, the combination with a main supporting member provided with means adapted to secure the same to a building, of platform supporting means slidably mounted upon said supporting member, a socket in said supporting member, a pawl on said sliding means adapted to engage with said socket, and means on said supporting member adapted to guide said pawl away from said socket when said sliding means is lowered.

2. In a shifting stage, the combination with a main supporting member provided with means adapted to secure the same to a building, of platform supporting means slidably mounted upon said supporting member, a platform, means mounted on said sliding means adapted to support said platform, a socket in said supporting member, a pawl connected to said sliding means adapted to engage with said socket, means on said supporting member adapted to guide said pawl away from said socket when said sliding means is lowered, and means adapted to raise and lower said platform.

Signed at Fall River, Mass., this 24th day of June, 1920.

CHARLES W. CLODFELTER.
